(57) **CLAIM**

The ornamental design for a cosmetic bottle, as shown and described.

DESCRIPTION

FIG. 1 is a front perspective view of the cosmetic bottle.

FIG. 2 is a front view of the cosmetic bottle shown in FIG. 1.

FIG. 3 is a right side elevation view of the cosmetic bottle shown in FIG. 1.

FIG. 4 is a top view of the cosmetic bottle shown in FIG. 1.

FIG. 5 is a bottom view of the cosmetic bottle shown in FIG. 1.

FIG. 6 is a front perspective view of a second embodiment of a cosmetic bottle.

FIG. 7 is a front view of the cosmetic bottle shown in FIG. 6.

FIG. 8 is a right side elevation view of the cosmetic bottle shown in FIG. 6.

FIG. 9 is a top view of the cosmetic bottle shown in FIG. 6.

FIG. 10 is a bottom view of the cosmetic bottle shown in FIG. 6.

FIG. 11 is a front perspective view of a third embodiment of a cosmetic bottle.

FIG. 12 is a front view of the cosmetic bottle shown in FIG. 11.

FIG. 13 is a right side view of the cosmetic bottle shown in FIG. 11.

FIG. 14 is a top view of the cosmetic bottle shown in FIG. 11.

FIG. 15 is a bottom view of the cosmetic bottle shown in FIG. 11.

FIG. 16 is a front perspective view of a fourth embodiment of a cosmetic bottle.

FIG. 17 is a front view of the cosmetic bottle shown in FIG. 16.

FIG. 18 is a right side view of the cosmetic bottle shown in FIG. 16.

FIG. 19 is a top view of the cosmetic bottle shown in FIG. 16; and,

FIG. 20 is a bottom view of the cosmetic bottle shown in FIG. 16.
